(57) **CLAIM**

The ornamental design for a modular chair component, as shown and described.

DESCRIPTION

FIG. 1 is a perspective view of a modular chair component showing a first embodiment of my new design.

FIG. 2 is a cross-sectional view of the modular chair component of FIG. 1, taken along line 2—2 of FIG. 1.

FIG. 3 is a front elevational view of the modular chair component of FIG. 1.

FIG. 4 is a right side elevational view of the modular chair component of FIG. 1, the left side view being a mirror image thereof.

FIG. 5 is a perspective view of a modular chair component showing a second embodiment of my new design, in which the frame is identical to the frame of the embodiment of FIG. 1, but the filler supported by the frame is different; and, FIG. 6 is a cross-sectional view of the modular chair component of FIG. 5, taken along line 6—6 of FIG. 5.
